UNITED STATES PATENT OFFICE.

JAMES E. BRADFORD, OF WEST DURHAM, NORTH CAROLINA.

DESIGN FOR A MONUMENT.

SPECIFICATION forming part of Design No. 37,086, dated August 9, 1904.

Application filed July 2, 1904. Serial No. 215,533. Term of patent 7 years.

To all whom it may concern:

Be it known that I, JAMES E. BRADFORD, a citizen of the United States, residing at West Durham, in the county of Durham and State of North Carolina, have invented a new, original, and ornamental Design for a Monument, of which the following is a specification, reference being had to the accompanying drawing, forming a part thereof.

In the drawing accompanying the specification and made a part thereof the figure is a

perspective view of a monument embodying my design.

What I claim as new, and desire to secure by Letters Patent, is—

The ornamental design for a monument as shown.

JAMES E. BRADFORD.
